CURTAIN HANGER

Ilse Tilgner, Stittsville, Ontario, Canada

Application October 4, 1956, Serial No. 613,996

1 Claim. (Cl. 16—87.8)

This invention relates in general to new and useful improvements in hangers of the type which are suspended from an overhead rail, and more specifically to an improved curtain hanger.

Heretofore curtains were mounted on hangers which in turn were supported by means of rollers on curtain supports or rails. The curtains were sewn to the hangers and when it was desired to hang the curtain, it was necessary to take down the rail, and then insert the rollers of the hangers in the rail. This was not only time-consuming, but also in certain instances the curtain was not properly secured to the hangers with the result that the curtain did not hang correctly. When this happened, it was necessary to remove the rail, take the curtain off, resew the curtain and then replace the curtain to determine whether the curtain was sewed properly on the hangers. Other means have been devised but none have proved satisfactory.

It is therefore the primary object of this invention to provide an improved curtain hanger which is so constructed whereby the curtain to be hung may be readily clamped to the curtain hanger and adjusted relative thereto in order that the curtain may be correctly hung without the necessity of sewing the curtain to the hanger and without the time-consuming process of cutting loose the threads and re-sewing the curtain in case the connection between the hanger and the curtain was improper.

Another object of this invention is to provide an improved curtain hanger which is provided with rollers for mounting on a curtain rail or track, the rollers being so mounted whereby they may be separated to facilitate the instant removal of a single hanger without the necessity of removing the entire curtain.

Another object of this invention is to provide an improved curtain hanger which includes a fixed roller and a movable roller, the rollers being mounted separately whereby an individual hanger may be removed from the track merely by separating the rollers thereof.

A further object of this invention is to provide an improved curtain hanger which includes clamp means for releasably reclamping a curtain thereto and the rollers for supporting the hanger on a track, the rollers being mounted separately to facilitate the placement and removal of an individual hanger.

These together with other objects and advantages which will subsequently become apparent reside in the details of construction and operation as more fully hereinafter described and claimed, reference being had to the accompanying drawing forming a part hereof, wherein like numerals refer to like parts throughout, and in which:

Figure 1 is a fragmentary vertical sectional view taken through a curtain and a supporting rail therefor, the curtain being shown as being secured on the rail by a hanger conforming to the spirit of the present invention;

Figure 2 is a front elevational view of the curtain hanger in Figure 1 and shows further details thereof;

Figure 3 is a sectional view taken substantially upon the plane indicated by the section line 3—3 of Figure 1

2

and shows the details of a latch member for retaining the clamped portion of the hanger in Figure 1 in a curtain clamping position, the latch member being shown in an inoperative position by dotted lines; and

5 Figure 4 is a side elevational view of a still further modified form of curtain hanger.

Referring now to the drawings in detail, it will be seen that there is illustrated in Figures 1 and 2 a curtain assembly which includes a curtain rail which is referred to in general by the reference numeral 10, a curtain 12, and a curtain hanger, which is referred to in general by the reference numeral 110. The curtain 12 may be of any construction and the curtain rail 10 of various constructions although it is preferred that it include a vertical supporting rib 16, an upper mounting flange 18 and a lower horizontal flange 20.

Referring now to Figures 1, 2 and 3, it will be seen that there is illustrated a form of curtain hanger which is referred to in general by the reference numeral 110. 20 The curtain hanger 110 includes an elongated body member 112 which corresponds generally in outline to the body member 22. Formed integral with the lower end of the body member 112 is a clamp element 114. The upper end of the body member 112 is rounded as at 116 and carries an axle 118, and journaled on the axle 118 is a roller 120.

Secured to the body member 112 is a roller support 122. As is best illustrated in Figure 2, the roller support 122 is disposed centrally of the body member 112 and is 30 connected thereto below the center line thereof. The upper end of the roller support 122 is provided with an axle 124 which is aligned with the axle 118 and which supports a roller 126. The roller 126 is disposed in alignment with the roller 120.

Also carried by the body member 112 is a clamp member 128. The clamp member 128 includes a clamp element 130 which is disposed in opposed relation to clamp element 114. The clamp member 128 also includes a support arm 132 which carries the clamp element 130, the support arm 132 being connected to the body member 112 above the center line thereof. As is best illustrated in Figure 2, the support arm 132 is bifurcated and includes a central opening 134 in which the lower part of the roller support 122 is disposed.

45 The roller support 122 and the support arm 132 are preferably formed of spring metal so that the roller 126 is urged against separation from the roller 120 and the clamp element 130 is urged in towards the clamp element 114. In order that the roller 126 may be retained relative to the roller 120 the position illustrated in Figure 1, 50 there is carried by an upper part of the body member 112 a latch member 136 which is of the spring type and which corresponds to the latch member 50. Also, in order that the clamp elements 114 and 130 may be retained in a curtain clamping position, there is carried by the lower part of the body member 112 a latch member 138. The latch member 138 is of the spring type and 55 engages the lower part of the support arm 132 as is best illustrated in Figure 3.

60 Referring now to Figure 4 in particular, it will be seen that there is illustrated another form of curtain hanger which is referred to in general by the reference number 140. The curtain hanger 140 is very similar to the curtain hanger 110 and includes a body member 142 and has disposed at the lower end thereof a clamp element 144. Carried by the upper part of the body member 142 is an axle 146 on which there is mounted a roller 148.

Hingedly connected to the lower part of the body member 142 is a roller support 150 which carries in its upper end an axle 152, and journaled on the axle 152 is a roller 154.

Also hingedly connected to the body member 142 is a

clamp member 156. The clamp member 156 includes a support arm 158 and a lower clamp element 160, the clamp element 160 being opposed to the clamp element 144 in cooperating therewith.

The curtain hanger 140 differs from the curtain hanger 110 in the provision of latch means for the roller 154 and the clamp element 160. The upper part of the body member 142 includes an internally threaded annular bore 162 in which there is threadingly engaged an elongated fastener 164 having a control knob 166. The opposite end of the fastener 164 is connected to the intermediate part of the roller support 150 by means of a swivel connection 168.

The body member 142 also includes a lower internally threaded annular bore 170. Threadingly engaged in the bore 170 is a fastener 172 having a control handle 174. The fastener 172 is connected to the support arm 158 by a swivel fitting 176. Thus it is possible to adjustably position the fasteners 164 and 172, and the positions of the rollers 148 and 154, and the clamp elements 144 and 160, respectively.

It is readily apparent that the hanger 140 will be used in the same manner as the hanger 110. Also, it will be readily apparent that the hangers, while described and illustrated as curtain hangers, will have other uses which will be obvious to those skilled in particular fields. In some instances it may be necessary to vary the arrangement of the clamp elements of the hangers. This, of course, will depend upon the particular article to be clamped therebetween.

The foregoing is considered as illustrative only of the principles of the invention. Further, since numerous modifications and changes will readily occur to those skilled in the art, it is not desired to limit the invention to the exact construction and operation shown and de-

scribed, and accordingly, all suitable modifications and equivalents may be resorted to, falling within the scope of the invention as claimed.

What is claimed as new is as follows:

- 5 A curtain hanger comprising an elongated body member, a roller journaled on an upper portion of said body member at one side thereof, a clamp element on a lower portion of said body member, a resilient roller support arm secured intermediately of said body member and 10 diverging therefrom toward the upper portion thereof, a second roller journaled on said roller support arm at one side thereof in confronting relation to said first roller, latch means extending transversely between intermediate upper portions of said body member and roller support arm normally retaining said rollers in axial alignment and permitting separation of said rollers, a resilient arm diverging from said body member toward a lower portion thereof, said resilient arm terminating at its lower end in a clamp element confronting said first mentioned clamp element, and a second latch means independent of said first latch means and extending transversely between intermediate lower portions of said body member and said resilient arm normally retaining the clamp elements together and permitting separation of said clamp elements 25 from each other independently of any change of distance between said rollers.
